UNITED STATES PATENT OFFICE.

JOHN H. BEASLEY, OF PETERSBURG, VIRGINIA.

TRUNK.

SPECIFICATION forming part of Letters Patent No. 753,033, dated February 23, 1904.

Application filed January 28, 1903. Serial No. 140,913. (No model.)

To all whom it may concern:

Be it known that I, JOHN H. BEASLEY, a citizen of the United States, residing at Petersburg, in the county of Dinwiddie and State of Virginia, have invented a new and useful Trunk, of which the following is a specification.

My invention relates to trunks, and has for its objects the features hereinafter described and more particularly claimed.

In the accompanying drawings, Figure 1 is a perspective view of one embodiment of my invention, parts being broken away. Fig. 2 is a transverse vertical section thereof with the tray in elevation and with the front section raised, and Fig. 3 is a perspective view showing a modification of the connector between the sections.

Similar characters indicate like parts throughout the several figures of the drawings.

The character T designates a trunk having a body portion 10 and a cover 11 preferably so hinged together that when the cover is open the upper edge of the body and the rearward side 12 of the cover will be at substantially the same level. When so opened, this side 12 should be approximately horizontal and is retained in such position by a stay consisting of two members 13 14, pivoted, respectively, to the body and cover at one side thereof and to each other. The member 13 is preferably provided with a shoulder 15, which contacts with the edge of the body and furnishes a positive stop which takes the weight off the pivot.

Preferably at each end of the extreme top of the body, with their upper face on a level with the edge thereof, are members 16 16, forming ways upon which the tray T may rest and move. An upwardly-projecting flange 17 at the outside of each of these ways prevents longitudinal movement of the tray. This tray is preferably formed in two sections 18 19, each of which is provided at or near its corners with suitable rollers 20, insuring almost frictionless movement by supporting the whole weight of the tray, which normally rests on the ways 16 and the rearward pair of which may be somewhat larger than the re-

mainder. The sections have at each end a connector C, comprising a member 21, secured to the rear section and provided with a substantially vertical slot 21^a and a member 22, pivoted at 23 on the forward section and having a projection 24 entering and moving freely along the slot and provided with an enlargement 24^a to prevent its withdrawal. The combined swing and travel of the member 22 about its pivot and along the slot in the companion member permits the front section of the tray to be turned up and rest upon the rear section for the purpose to be herein-after stated. A stop 25, fixed at each end of the tray-section 18, contacts with the member 21 and prevents the projection from sticking in its downward movement through the slot when the section is being lowered. In Fig. 3 of the drawings is illustrated a modification of this connector in which a stay 26 is pivoted at 27 upon the section 18 and has a longitudinal slot 28, which works over a projection on the section 19 and allows a like raising and lowering of the front section.

At the inner side of each end of the trunk-cover is provided a working face 30, here shown as formed upon the upper edge of the member 31, secured thereto. As illustrated, this face is inclined and is of curved contour, with stop-faces 32 at each end. Upon each end of the rear tray-section is a projection 33, preferably provided with a roll 34, co-operating with the face 30. It will be seen that when the cover is raised the face 30 will slightly raise and simultaneously draw back the tray, the rollers of which travel along the ways, the rear pair being lifted by the face over the space between the body and cover and falling when the cover is fully raised upon the side 12 thereof with the back of the tray in close proximity to the top of the cover. This gives access to a considerable portion of the body, and to make this complete the section 18 may be raised upon the section 19, the construction permitting this in the manner previously described. The faces 32 may serve to prevent excessive movement or disengagement of the coacting projection.

It is evident that in operation my improved trunk easily and automatically moves the tray

to open the body portion, that the whole of said body is left available for packing, and that these results are attained without weakening any part of the structure.

5 Having thus described my invention, I claim—

1. The combination with a trunk provided with ways and a cover for said trunk provided with an elongated inclined curved working 10 face, of a tray having a projection coacting with the working face to move the tray over the ways when the cover is raised or lowered.

2. The combination with a trunk provided with ways and a cover for said trunk provided 15 with an inclined curved working face having spaced stops, of a tray having a projection coacting with said working face to move the tray over the ways.

3. The combination with a trunk provided 20 with ways and a cover for said trunk provided with an inclined curved working face having stop-faces at each end thereof, of a tray having a projection coacting with the working face to move the tray over the ways.

25 4. The combination with a trunk provided with ways, of a movable tray consisting of a plurality of sections, and a connector for the sections comprising a member attached to one

of the sections and provided with a slot and a projection carried by the other section and 30 entering said slot.

5. The combination with a trunk, of a movable tray consisting of a plurality of sections and a connector for the sections comprising a member attached to one of the sections and 35 provided with a slot and a member pivoted to the adjacent section and having a projection entering the slot.

6. The combination with a trunk, of a movable tray consisting of two sections, one of 40 which may be raised upon the other, and a connector for these sections comprising a member attached to one of the sections and provided with a slot, a member pivoted to the adjacent section and having a projection 45 entering the slot, and a stop with which the pivoted portion of the connector may contact as it is lowered from its raised position.

In testimony that I claim the foregoing as my own I have hereto affixed my signature in 50 the presence of two witnesses.

JOHN H. BEASLEY.
